TABLE

Gooding N. Kelly, Chicago, Ill., and Lester Wuenn,
Michigan City, Ind., assignor to The Dearborn
Company, Chicago, Ill., a corporation of Illinois

Application January 20, 1934, Serial No. 707,510

7 Claims. (Cl. 311—52)

This invention relates to tables and it is particularly useful in small dining room tables of the refectory type.

The object of the invention is to enable a table to be extended by supporting a detached leaf solidly and securely thereon in a novel manner and in the same plane with the top of the table.

Another object of the invention is to utilize a drawer of the table to support a detached leaf and to provide simple means for interengaging the leaf with the table top and the drawer to hold the leaf securely in place in the plane of the table top.

And a further object of the invention is to provide a leaf with means whereby it may be engaged with the table top and an open drawer in a manner to secure the leaf tightly and firmly in place upon the drawer and in proper relation to the table top to form a solid extension of the top in the plane thereof.

In the drawing we have illustrated the invention in a simple embodiment of a refectory type of table and referring thereto.

Fig. 1 is a top plan view of a table showing the frame of the table and the extension leaf supported in place on the drawer in broken lines.

Fig. 2 is a fragmentary bottom plan view of the table showing the extension leaf and the table top partly broken away and the cleats of the extension leaf arranged within the open drawer of the table.

Fig. 3 is a sectional view on the line 3—3 of Fig. 1 showing, in broken lines, the manner in which the extension leaf is installed in position.

Fig. 4 is a sectional view on the line 4—4 of Fig. 2.

Referring to the drawing, 5 indicates generally the frame of the table which has a fixed top 6 and a drawer 7 arranged to slide in any suitable guides through an apron 8 of the table. The drawer is limited in its outward movement by stops 9 which may be fastened to the underside of the top 6 and in its inward movement by stops 10 which are shown fastened to the apron 11. We have shown a drawer having a depth substantially equal to the width of the table and the stops 9 are located to limit the outward movement of the drawer so that it will support the extension leaf 12 without projecting beyond the outer edge thereof. The location of the stops 9 and 10 will depend upon the depth of the drawer and the extent of opening movement of the drawer desired and the position thereof may be varied accordingly.

Cleats 13 are fastened to the underside of the

extension leaf 12 and they are spaced apart so that they will fit snugly within the drawer between the sides 14 thereof. The cleats are arranged so that ends 15 project beyond the inner edge of the leaf to engage beneath that part of the table top which overlaps the drawer when opened. The edges of the table top may be square but we prefer that they be chamfered, at least the edge 16 with which the extension leaf engages, and the engaging edge of the extension leaf should be shaped to complement the edge of the table top which it engages to assist in forming a tight joint. The ends 17 of the cleats are preferably rounded so that they will ride over the top edge of the drawer front 18 when the extension leaf is installed. 15 Tapered wedges 9' are secured to the top 6 rearwardly of the stops 9 and as the drawer moves to its full open position the rear rail thereof rides over these wedges thereby pivoting the front of the drawer upwardly to compensate for play of 20 the drawer in its support and hold it firmly in position to insure support of the extension leaf in the plane of the table top. The stops 9 limiting outward movement of the drawer are located and the cleats are so arranged on the extension 25 leaf that when the drawer is opened full and the extension leaf is installed the rounded ends of the cleats in sliding over the top edge of the drawer front pull the drawer over the wedges 9' and against the stops 9, and the cleats will wedge 30 against the drawer front as the extension leaf comes to rest upon the drawer and the extended ends 15 of the cleats clamp beneath the table top so that the drawer is rigidly held in open position and the extension leaf is rigidly and solidly 35 supported upon the drawer and snugly against the edge of the table and in the plane of the top to afford a smooth extension thereof. The sides of the drawer may be extended as at 19 beyond the drawer front 18, at least as far as the drawer 40 pull 20, to extend the support for the extension leaf if desired.

The invention provides a simple and convenient means for extending the top of a table and it is particularly useful in connection with small dining room tables of the refectory or refectorette type. We have shown the invention in a table designed to be extended at one side only but it will be readily understood that the depth of the drawer may be reduced and another drawer provided at the opposite side of the table so that the table could be extended at both sides; and it will be equally understood that provision may be made for extending the table at the ends instead of at the sides or at both ends and sides, it 55

being only necessary to provide the drawers where needed. It is a very simple and easy operation to install the leaf because it is only necessary to open the drawer and put the leaf in place thereon in the manner indicated in broken lines in Fig. 3. The extended ends of the cleats take under and engage the edge of the table top and the rounded edges 17 of the cleats ride against the top of the drawer front and snugly between the sides of the drawer until the leaf rests upon the drawer. Thus the cleats cooperate with the drawer and the stops 9 to hold the leaf tightly against the table top and the extensions 15 of the cleats hold the leaf in place on the drawer. The leaf is supported in place entirely by the drawer and it is secured on the drawer in the plane of the top of the table without employing any fastening devices that require manipulation. The cleats cooperate with the sides of the drawer to prevent endwise displacement of the leaf and with the table top to hold the leaf on the drawer, and thus the cleats form the sole means for securing the leaf to the table.

While we have shown and described the invention as adapted for extending a small dining room table at one side thereof we have indicated sufficiently to those skilled in the art that the invention may by duplication be employed for extending both sides or both ends and sides of the table, and tables of any kind to which it is or may be adapted, and we reserve the right to make any changes that may be required for adapting the invention for these various uses within the scope of the following claims.

35. We claim:

1. In a table having a top, a drawer, a support for the drawer whereby the drawer may be slid beneath the top and to open position beyond an edge of the top, and tapered wedges on the underside of the top and engageable with the drawer when in open position to bind the drawer rigidly in its support.
2. The combination of a table having a top, a drawer arranged to slide beneath the top to open position beyond an edge thereof, an extension leaf adapted to be supported on the drawer in open position and against the adjacent edge of the table top and in the plane of the top, means on the underside of the extension leaf cooperating with the drawer and table top for holding the extension leaf on the drawer, and tapered wedges on the underside of the top and engageable with the drawer to firmly hold the drawer when in open position and insuring rigid support of the extension leaf in the plane of the top.
3. In a table having a top, a drawer including front, rear and side rails, a support for the drawer whereby the drawer may be slid beneath the top and to open position beyond an edge of the top, and tapered wedges on the underside of the top and engageable with the rear rail of the drawer when in open position to bind the drawer rigidly in its support.
4. In a table having a top, a drawer including front, rear and side rails, a support for the drawer whereby the drawer may be slid beneath the top and to open position beyond an edge of the top, means on the top and engageable with the rear rail of the drawer to limit sliding movement of the drawer to open position, and tapered wedges on the underside of the top and engageable with the upper edge of the rear rail of the drawer when in

open position to bind the drawer rigidly in its support.

5. The combination of a table having a top, a drawer including front, rear and side rails and arranged to slide beneath the top and to open position beyond an edge thereof, an extension leaf adapted to be supported on the drawer when in open position and against the adjacent edge of the table top and in the plane of the top, cleats secured to the underside of said extension leaf and spaced apart to engage the side rails of the drawer to prevent movement of the extension leaf transversely of the drawer and the table top, said cleats projecting beyond the edge of the leaf which engages the table top and being extended beneath the underside of the table top at the edge which engages the leaf and cooperating with the drawer to hold the leaf in the plane of the top, said cleats being terminated inwardly of the edge opposite the edge of the leaf engaging the table top whereby such inwardly disposed ends of the cleats engage the front rail of the drawer, and means for limiting movement of the drawer to open position whereby engagement of the cleats with the front rail of the drawer firmly wedges the extension leaf against the adjacent edge of the table top.

6. The combination of a table having a top, a drawer including front, rear and side rails and arranged to slide beneath the top and to open position beyond an edge thereof, an extension leaf adapted to be supported on the drawer when in open position and against the adjacent edge of the table top and in the plane of the top, cleats secured to the underside of said extension leaf and spaced apart to engage the side rails of the drawer to prevent movement of the extension leaf transversely of the drawer and the table top, said cleats projecting beyond the edge of the leaf which engages the table top and being extended beneath the underside of the table top at the edge which engages the leaf and cooperating with the drawer to hold the leaf in the plane of the top, said cleats being terminated inwardly of the edge opposite the edge of the leaf engaging the table top whereby such inwardly disposed ends of the cleats engage the front rail of the drawer, means for limiting movement of the drawer to open position whereby engagement of the cleats with the front rail of the drawer firmly wedges the extension leaf against the adjacent edge of the table top, and tapered wedges on the underside of the table top and engageable with the rear rail of the drawer and firmly holding the drawer when in open position and the rear rail is engaged with the limiting means and insuring rigid support of the extension leaf in the plane of the table top.

7. In a table having a top, a drawer, a support for the drawer whereby the drawer may be slid beneath the top and to open position beyond an edge of the top, stops for limiting sliding movement of the drawer to open position, wedges on the stops engageable with the drawer when in open position to bind the drawer rigidly in its support, and an extension leaf adapted to be supported on the drawer in open position and against the adjacent edge of the table top and in the plane of the top.
